UNITED STATES PATENT OFFICE.

ROBERT B. WOODWORTH, OF PITTSBURGH, PENNSYLVANIA.

TUG WHEEL-RIM.

1,334,688.

Specification of Letters Patent. Patented Mar. 23, 1920.

Application filed December 5, 1917. Serial No. 205,687.

To all whom it may concern:

Be it known that I, ROBERT B. WOODWORTH, a citizen of the United States, and resident of Pittsburgh, in the county of Allegheny and State of Pennsylvania, have invented certain new and useful Improvements in Tug Wheel-Rims, of which the following is a specification.

My invention relates to the construction 10 of wheel rims, and more particularly the construction of the tug rims of the bull wheels and band wheels forming part of well drilling rigs.

One object of this invention is to provide 15 a tug rim of novel construction which combines great strength and rigidity with a minimum weight and which is easily constructed and readily assembled and dismembered in the application and use of the rim.

20 A still further object of the invention is the provision of a wheel rim having the novel details of construction and the arrangement of parts shown in the drawings, more fully described hereinafter, and particularly pointed out in the appended claim.

Referring now to the drawings, forming 25 part of this specification, Figure 1 is a plan, partly in section, showing the bull wheel of a well drilling rig having a sectional tug rim thereon embodying the novel features of my invention.

Fig. 2 is an end elevation showing details 30 in the construction of the apparatus shown in Fig. 1.

Fig. 3 is a transverse section, showing details 35 in the construction of the brake rim on the bull wheel of Fig. 1, the section being taken on the line III—III of Fig. 1.

Fig. 4 is a transverse section, on the line 40 IV—IV of Fig. 1, showing the adjustable spool forming part of the bull wheel of Fig. 1.

Fig. 5 is a transverse section, on a larger 45 scale, showing details in the construction of a pressed steel tug wheel rim embodying my invention, the section being taken on the line V—V of Fig. 2 or Fig. 6.

Fig. 6 is a plan showing the band wheel 50 of a well drilling rig having a tug rim constructed and arranged and applied for use thereon in accordance with my invention.

Fig. 7 is an end elevation, partly in section, showing details in the construction of the band wheel of Fig. 5.

In the accompanying drawings, the bull 55 wheel and band wheel tug rims embodying the novel features of this invention are designated generally by the letter A. As shown in Figs. 1 to 4, the tug rim A forms part of the bull wheel of a well drilling rig. 60 In Figs. 6 and 7, the tug rim A is shown applied to the band wheel of such well drilling rig.

The tug rim A, as is most clearly shown in Fig. 5, is made from a thin rolled steel 65 plate, of substantially uniform thickness, which is pressed or stamped between suitable forming guides so as to form a transversely flat or straight peripheral surface 2 and having integral flanges 3, 3 at the edges 70 defining the width of the tug rim, the flanges 3 extending inwardly, in substantial parallel planes. The rim A shown, is formed of four duplicate sections or segments, (the number of sections being governed ordinarily by the, 75 diameter of the wheel rim) and each section is curved lengthwise to a predetermined radius in order to form a rim of the desired diameter. Two parallel encircling indentations are pressed into the flat periphery 2 of the rim sections to form rope 80 grooves 4 and 5 for the bull ropes used in transmitting power from the band wheel to the bull wheel of a well drilling rig, and the grooves, which may be made semi-circular in cross section, preferably are formed with flat inwardly converging sides 6, 6 in the manner shown in Fig. 5.

In the bull wheel shown in Figs. 1 to 4 the sectional tug rim A is connected by converging spokes 7 to one end of the tubular bull wheel shaft B, this shaft having a gudgeon 8 on each end. The gudgeons have spiders 9 which fit tightly into the ends of the shaft B and the spiders are provided at 95 one end with a peripheral flange 10 which engages with the end of the bull wheel shaft to assist in locating and maintaining the gudgeons 8, 8 in axial alinement with the shaft B. (See Fig. 1.) Rivets 11 are used 100 to secure the gudgeons to the shaft, although any other approved fastening means may be employed.

Each section of the tug rim A is provided with two of the spokes 7, which are shown 105 rigidly fastened at one end by gusset plates 12 and rivets 13 to the rim sections. The inner ends of the spokes 7, which may be

conveniently made of rolled steel channel beams, extend between the parallel faces of the annular legs of the two flanges 14, 14, the flanges 14 being riveted to the shaft B, 5 and bolts 15 being employed to detachably fasten the spokes 7 to the flanges 14. The abutting ends of the rim section are detachably connected by splice plates 16 on the marginal flanges 3, 3 thereof, which are 10 fastened by rivets 17 to the flanges 3, 3 at one end of the rim section and which are secured by bolts 18 to the flanges 3, 3 at the abutting end of an adjoining rim section.

The gudgeon side of the tug rim A is provided with a dog 19 and a series of helpers 20, 21, and 22 which are formed of bent bars, the dog extending outwardly from the side of the rim and being riveted to one of the rim sections, the helpers which also extend 20 outwardly being riveted to the spokes 7 of the tug rim. The helpers 20, 21, and 22 are positioned at successively greater distances from the periphery of the rim A, the dog and helpers being employed to assist 25 in shifting the bull ropes in removing and replacing these ropes on the tug rim A of the bull wheel, as is frequently necessary in the operation of the bull wheel.

That portion of the bull wheel shaft B 30 adjacent to the tug wheel is employed to store unused portions of the well drilling cable and in order to provide sufficient storage capacity, a spool C is adjustably secured on the shaft, the spool being arranged 35 to move toward and away from the tug rim A. As shown, the arms of this spool are formed of rolled steel channels 23 which are detachably connected to one another by suitable bolts 24 and which have a clamp 25 40 thereon by which the spool is frictionally held in adjusted position on the shaft.

The spool side of the tug rim A is provided with a series of turning pins 28 which are conveniently formed in this case of a 45 short piece of wrought metal pipe and a bolt 29 which extends through the pipe and through suitable holes in the flanges 3 of the tug rim. The turning pins 28 are employed to rotate the bull wheel manually in removing 50 and replacing the bull rope on the tug rim A in the usual and well known manner.

Secured on the turning pin side of the tug wheel is a series of cable protectors 30 having inwardly bent ends, these protectors 55 being made of flat bars and being riveted to one end of the Z-shaped knees 31, the other end of the knees being detachably fastened to the spokes 7 by bolts 32. The edges of the cable protectors 30 are rounded to prevent 60 cutting or fraying of the drilling cable in winding and unwinding the cable on the shaft B, these protectors being provided on alternate spokes 7 to prevent the drilling cable from fouling on the tug rim turning 65 pins 28.

The bull wheel shaft B is also provided at one end with the usual brake wheel D, which, as shown, is made in sections and has a laminated wooden brake rim formed of wooden cants 26 which are fastened to the 70 outer ends of spokes 27, the spokes being detachably secured to the shaft B in the same manner as the spokes of the tug rim A. The brake wheel also has cable protectors 30 which are fastened on the spool side of the 75 bull wheel in the same manner as on the tug rim and turning pins 29 which are made of wood, are tightly driven in holes of suitable size in the gudgeon side of the brake wheel to provide means for manually turning the 80 bull wheel from the brake wheel end of the bull wheel shaft. The brake wheel D, not forming part of this invention, its construction is not further described.

In the band wheel construction shown in 85 Figs. 6 and 7, the band wheel E is built up solidly of a series of boards or planks 33 so as to make a laminated wooden wheel. This wheel is provided with a shaft 34 by which it is supported in suitable bearings, the shaft 90 being keyed to the metal hubs 35, 35 of which there is one on each side of the web of the wheel E, and the hubs are fastened by through bolts 36 to the web of the wheel E. This wooden band wheel construction in 95 itself is an old and well known construction.

Secured on one side of the band wheel E so as to be concentric with the periphery of this wheel, is a sectional metal tug rim A embodying the novel features of my invention. This tug rim is essentially the same as has been described in connection with Figs. 1 to 5. In the case of the band wheel E there are no spokes, however, connecting the rim to the shaft for the wheel, and a series 105 of brackets 37 and 38 are employed in fastening the tug rim A to the side of the wooden band wheel E. (See Figs. 6 and 7.) Similar brackets may be used to fasten these rims to all metal wheels.

As shown, the brackets 37 are formed of short pieces of rolled steel channel beams, one flange of the beams being provided with holes through which the bolts 36 extend in fastening the rim sections to the band wheel, 115 the bolts 36, of which there are two for each bracket, also extending through registering holes in the web of the band wheel E. A bracket 37 is provided on one end, and a second bracket 38 at an intermediate point in 120 the length of each section of the tug rim A, these brackets being fastened by rivets to the flanges 3 of the rim sections.

The brackets 37 at the ends of the rim sections have a short piece of channel beam 40 125 riveted thereto, the two pieces of channel beam 37, 40 being placed back to back so that the flanges of the shorter section will project outwardly and these outwardly projecting flanges are provided with holes 130

which register with similar holes in one end of the flanges 3 of the rim sections. Bolts 41 which extend through these registering holes detachably fasten the abutting ends of 5 the rim sections to one another.

The bull wheels and band wheels equipped with my improved tug rim will be operated in the usual and well known manner.

The advantages of my invention will be 10 apparent to those skilled in the art. My improved pressed steel tug rim provides a detachable rim which is easily and quickly erected and dismembered and transported from place to place. The sectional tug rim 15 is strong and durable and combines great strength and rigidity with a minimum weight.

Various changes in the details of the construction of the tug rim may be made without departing from my invention as defined 20 in the appended claim.

I claim:—

In a bull wheel the combination with a shaft, of a tug rim at one end thereof, the periphery of said rim having rope grooves 25 therein, said rim being formed of a plurality of sections and each of said sections being formed of a rolled steel plate of substantially uniform thickness, the peripheral surface of the rim sections being curved to 30 a predetermined radius with an integral inwardly extending flange at the edges defining the rim width, said flanges extending substantially at right angles to the plane of said peripheral surface, and means connect- 35 ing the rims to the shaft, said means being secured to the flanges of the rim sections and detachably connected to said shaft.

In testimony whereof I have hereunto set my hand.

ROBERT B. WOODWORTH.
